United States Patent Office

Des. 182,210

Patented Feb. 25, 1958

182,210

LAVATORY

Lee K. Watkins, Louisville, Ky., assignor to American Radiator & Standard Sanitary Corporation, New York, N. Y., a corporation of Delaware

Application December 13, 1955, Serial No. 39,318

Term of patent 14 years

(Cl. D4—2)

Fig. 1 is a view in perspective of a lavatory embodying my new design,

Fig. 2 is a top plan view of the lavatory,

Fig. 3 is a view in front elevation of the lavatory, and

Fig. 4 is a side view of the lavatory.

I claim:

The ornamental design for a lavatory, substantially as shown.
